UNITED STATES PATENT OFFICE.

ALBERT T. BEMIS, OF INDIANAPOLIS, INDIANA, ASSIGNOR TO THE STANDARD DRY-KILN COMPANY, OF SAME PLACE.

LUMBER-TRUCK.

SPECIFICATION forming part of Letters Patent No. 569,992, dated October 27, 1896.

Application filed February 17, 1896. Serial No. 579,544. (No model.)

To all whom it may concern:

Be it known that I, ALBERT T. BEMIS, a citizen of the United States, residing at Indianapolis, in the county of Marion and State 5 of Indiana, have invented certain new and useful Improvements in Lumber-Trucks; and I do declare the following to be a full, clear, and exact description of the invention, such as will enable others skilled in the art to which 10 it appertains to make and use the same, reference being had to the accompanying drawings, and to the letters of reference marked thereon, which form a part of this specification.

15 This invention relates to certain new and useful improvements in trucks for use in lumber dry-kilns; and it has for its object the provision of a simple and efficient truck of the character described.

20 The truck consists, essentially, of two longitudinal strips of thin channel-steel, which are held at the required distance apart by means of "spreaders" or hollow cylindrical washers, through which bolts are passed.

25 The essential feature of the invention resides in the peculiar construction of the washer, whereby the side strips of the truck-frame may, by tightening the nuts upon the bolts, be sprung inward sufficiently to cause 30 the nuts upon the bolts to be securely held or locked against possible accidental displacement.

To this end and to such others as the invention may pertain the same consists in the 35 novel features of construction hereinafter described, shown in the accompanying drawings, and then specifically defined in the appended claims.

The invention is clearly illustrated in the 40 accompanying drawings, which, with the letters of reference marked thereon, form a part of this specification, and in which drawings—

45 Figure 1 is a side elevation of a lumber-truck embodying my invention. Fig. 2 is a top plan view of the same, and Fig. 3 is a vertical transverse section upon the line 3 3 of Fig. 1.

50 Reference now being had to the details of the drawings by letter, A and A are two strips of thin angle-steel, or more properly termed "channel-steel," which are held securely at the required distance apart by

means of spreaders or washers B, which are interposed between the strips A at suitable points. The wheels, which are grooved to 55 fit the track upon which they are designed to run, are journaled in openings provided for the purpose in the side strips A, and are preferably provided with roller or ball bearings. 60

The spreaders or washers B are preferably cylindrical and hollow, being cast each in a single casting, or, if preferred, the heads or ends B' may be independent of the body portion of the washer. The heads or ends B' 65 are provided with a central opening, through which is passed the bolt D, and the head B' at the point which immediately surrounds the central bolt-opening is thickened, as shown at B². The thickness of the washer at 70 the center, through which the bolt is passed, is slightly less than the length of the body portion of the washer, so that the side strips or plates A A will be sprung inward at the point at which the bolt passes through the 75 washer, as clearly shown in Fig. 3 of the drawings. The inner surface of the strip A upon each side of the washer will be furnished with a substantial bearing against the thickened portion B² of the washer-head, and 80 the tendency of the plate or strip to spring outward will serve to effectually prevent the possibility of the nuts upon the bolt from working loose, as will be readily understood.

Having thus described my invention, what 85 I claim to be new, and desire to secure by Letters Patent, is—

1. In a truck for use in lumber-drying kilns, two parallel side pieces A, A, the wheels having their axles journaled in openings formed 90 in said side pieces, the washers or separators B interposed at intervals of the length of the truck and serving to hold the side pieces at the required distance apart, the said washers B being hollow and having central openings for the passage of a securing-bolt, the thickness of the washer at the point at which the bolt passes through it being less than at the periphery of the washer, substantially as described and for the purpose specified. 95

2. A washer designed for separating the channel-steel strip forming the frame of a lumber-kiln truck, of the character described, the said washer consisting of a hollow body 100

portion having apertured ends for the passage of a securing-bolt, the ends being provided with a thickened portion surrounding the central bolt-opening and the length of 5 the washer at the point at which the bolt passes through it being less than at the outer face of the washer, substantially as described.

In testimony whereof I affix my signature in presence of two witnesses.

ALBERT T. BEMIS.
